Application filed September 19, 1893. Serial No. 485,916. Term of patent 3½ years.

To all whom it may concern:

Be it known that I, CHARLES BOOZE, a citizen of the United States, residing at Buffalo, in the county of Erie and State of New York, 5 have invented and produced a new and original Design for Wall-Paper, of which the following is a specification.

The design consists of wreath-like ornaments placed at equal distances apart over 10 the surface of the paper, said ornaments being formed by two sprays of fern leaves forming an open wreath in which are upright sprays of flowers as represented in the accompanying drawing.

15 In the upper or border portion of the design the tops of the sprays of ferns forming the wreath ornaments terminate in reversely

curved scrolls and the adjacent ornaments are connected by sprays of flowers which are entwined with the sides thereof.

20 A narrow band composed of connected scroll like ornaments separates the body and border portions of the design.

What I claim is—

1. The design for wall paper herein shown 25 and described.

2. In the design for wall paper the border herein shown and described.

Witness my hand this 15th day of September, 1893.
